CLAIM

The ornamental design for a mechanical toy, as shown and described.

DESCRIPTION

1. Mechanical toy

1.1 is a front perspective view;

1.2 is a front view;

1.3 is a rear view;

1.4 is a bottom front perspective view;

1.5 is a top rear perspective view;

1.6 is a side view and

1.7 is a side view.

The toy has 4 identical convex hexagonal faces and 4 identical planar triangular faces. The pieces on each face are generated by 4 pairs of cutting planes, each of which is parallel to a planar triangular face, respectively; for example of fig. 1.2, the two cutting planes and the upper triangular face are shown as the horizontal lines; the group of pieces on the upper triangular face can rotate about the vertical axis; similarly, that on the lower hexagonal face can also rotate about the vertical axis.
